WEATHERSTRIP

Walter H. Hardgrave, Albuquerque, N. Mex.

Application September 27, 1950, Serial No. 187,059

10 Claims. (Cl. 20—66)

1

The present invention relates to protectors for doors and windows and has for its main purpose the sealing of the bottom of the door against weather, wind, ingress of dust, moisture, vermin, etc.

This invention involves an improved type of weather seal for doors and windows which is extremely effective in operation, which is uncomplicated and easy to manufacture, fabricate and install and which is of extremely rugged construction and designed for unlimited periods of service. The present device moreover has the outstanding characteristic that the top member thereof may be easily removed for purposes of cleaning the sill or threshold.

One object of the present invention then is to provide a device of the character described which will have weather stripping characteristics operable to completely seal any gap that there might otherwise be between the door or window and door or window sill.

Another object of the present invention is to provide a device of the character described which will have flanges which may be bent to any desired position to provide for installation in rooms having wall to wall carpeting and the like.

Still another object of the present invention is to provide a device of the type described which will have a removable cap member which is normally held in place by a latching mechanism and yet which may be easily and quickly removed from the stationary body portion when desired.

Yet another object of the present invention is to provide a device of the character described in which the movable cap member of the device is interchangeable with various stationary body forms of the invention, so that the device may be readily and quickly installed in a wide variety of applications.

Still another object of the present invention is to provide a device of the character described in which the movable cap member normally lies flat or flush with the stationary body member, said cap member being further adapted to rise or be elevated above the structure when the door or window is being closed.

A still further object of the invention is to provide the door or window with an adjustable actuating element by means of which the movable cap member is brought from its normal flush position to its elevated position when actuated by the closing door or window, so as to provide effective sealing means and slope for drainage of water.

With the above and other objects in view as

2

will appear as the description proceeds, the invention resides in the novel construction, combination and arrangement of parts, as herein-after more specifically set forth, claimed and shown in the accompanying drawings which form a part of this application for Letters Patent.

In the accompanying drawings are shown several preferred and practical embodiments of the invention, it being understood, however, that the drawings are merely illustrative and that the inventive-concept is susceptible of other embodiments and utilizations, and that the illustrated embodiments likewise are susceptible of a wide range of variation and modification without departing from the spirit of the invention or the scope of the appended claims.

In these drawings which accompany and form a part of this specification, and in which like reference numerals are used to designate the same or like parts throughout the several figures:

Fig. 1 is a sectional view of a door structure with a preferred form of the improved weather strip of my invention applied thereto;

Fig. 2 is an inverted perspective view of one of the locking cams for the movable cap member;

Fig. 3 is a perspective detail view with cap member 36 cut away showing the locking cam shown in Fig. 2;

Fig. 4 is a sectional view of a door structure with another form of the improved weatherstrip of my invention applied thereto, and showing another form of latching member applied in connection therewith;

Fig. 5 is a detail perspective view showing the latching mechanism of Fig. 4 with the movable cap member removed;

Fig. 6a is a view of the latching mechanism shown in Fig. 5 taken along line 6a—6a; and,

Fig. 6b is a view taken along line 6b—6b of

Fig. 5;

Fig. 6c is a view taken along line 6c—6c of Fig. 5;

Fig. 6d is a view of a detail of Fig. 5;

Fig. 6e is a detail view of the latch member of Fig. 5; and

Fig. 7 is a sectional view of a casement window structure showing still another form of the improved weather strip of my invention applied thereto.

Referring now in detail to the drawings and first adverting to that form of the invention shown in Fig. 1, the reference numeral 12 has been used generally to designate the improved stationary body portion of my invention. The weatherstrip 14 may be secured to a sill or thresh-

old 16 by any suitable means, such as, for example, the screw member 18. The door which is to be sealed has been indicated by the reference numeral 20. Reference numeral 14 has been used to generally designate the stationary body member, the cross-sectional shape of which is illustrated most clearly in Fig. 1. The stationary body member has leg portions 24 and 26 which contact the sill or threshold 16, there also being slanting flange members 28 and 30 which also contact the sill or threshold 16 as is shown most clearly in Fig. 1. A web member 32 having slanting and horizontal portions runs between the legs 24 and 26 as shown. The slanting flange members 28 and 30 each have a groove 34 extending the length thereof, said groove enabling the user to bend the slanting flange members 28 and 30 up as shown in dotted lines in Fig. 1, or down to provide contact with uneven sills or thresholds 16 as may be desirable in certain applications such as, for example, when wall-to-wall carpeting 102 is used.

The movable cap member of the device has been generally indicated by the reference numeral 36 and comprises a generally rectangular strip having at one side thereof a downwardly extending longitudinal rib 38 which, with the flanges thereon, provides two horizontal grooves 40 and 42, one on each side of the rib, as is shown most clearly in Fig. 1. The groove 42 of the longitudinal rib 38 engages with a flange 74 to form a pivotal tongue and groove connection around which the movable cap member 36 may revolve, and said tongue and groove connection being of such character that when the cap member is pivotally moved upwardly toward the lower edge of the door, a cramping and binding action is present in the tongue and groove connection to effect an air-tight seal.

Figs. 2 and 3 show a cam latch member which has been generally designated by the reference numeral 46. The cam latching members 46 are secured to the underside of the movable cap member 36 by suitable fastening means, such as the bolt member 48, the cam latch 46 being fixedly secured to said bolt member 48 by threading in cap member 36 and bradding under member 46 so that turning the bolt 48 will also turn the cam latch 46. The cam latch member 46 has the shape shown in Fig. 2 and has a flat side 50 adapted to engage in the groove 40 in the cap member 36 which has previously been described. The cam latch 46 also has a flat edge 52 which is adapted to fit into the groove 54 in the stationary body member 14. (See Fig. 1.) The reference numeral 56 designates a coiled spring which encircles the bolt 48, one end of the spring 56 being attached to the cam latch 46 and the other end engaging the groove 40 as is shown most clearly in Figs. 2 and 3. The latching cams 46 normally hold the movable cap member 36 down against the stationary body member 14 so that the movable cap member will lie flat against the stationary body member when the door 20 is open, and they also provide means whereby the movable cap member 36 may be easily and quickly removed from the stationary body member 22 for cleaning and like purposes. This is accomplished by turning the bolt 48 through $\frac{1}{4}$ of a turn, thus also turning the cam latch 46 to the position shown by means of the dotted lines in Fig. 2, thus removing the side 52 out of engagement with the groove 54 in the stationary body member 22 so that the movable cap member 36 may be pulled out of engagement with the flange 44 whereby 70

the movable cap member 36 may be removed from the device, and the device cleaned of accumulated dust and debris. After the device has been cleaned the movable cap member 36 may be slipped back into position so that the groove 42 of the longitudinal rib 38 again engages the flange 44, after which the movable cap member is pressed down against the stationary body portion 22 and the bolt 48 given $\frac{1}{4}$ of a turn back, whereby the edge 52 of the cam latch 46 again engages the groove 54 in the position shown by the solid lines in Fig. 2, thus latching the movable cap member 36 in place.

The door 20 carries a hook member 58 which may be fixedly secured to the door 20 by any suitable means such as, for example, the screws 60. The hook member 58 is adapted by bending the leading corner downward to slip into a notch under the movable cap member 36 by a scissoring action as the door 20 is closed, thus lifting up the movable cap member 36 as is shown most clearly in Fig. 1 and providing an effective weather seal to prevent the entrance of wind, dust, debris and vermin between the bottom of the door 20 and the threshold or sill 16. The notch is not visible in Fig. 1; however, this same structural detail will be described in connection with a later figure. When the door 20 is opened the hook 58 moves out from under the movable cap member 36 and the spring 56 urges the movable cap member down against the stationary body member 22 so that the movable cap member 36 will lie flat against the stationary body member 14 so that users of the door will not accidentally be tripped by the movable cap member 36 when crossing the threshold. If desired, a suitable wiper strip 62 may be carried by the door 20 to which it is fixedly secured by any suitable means, such as, for example, the screws 64. The wiper strip 62 provides additional weatherstrip protection between the bottom of the door 20 and the threshold 16.

If desired, suitable weep holes (not shown) may be provided in the device 14 to afford adequate drainage for water and the like which may enter the device. Further, as an additional protection against the entrance of wind and dust and the like, suitable material 66, such as putty or the like may be placed around the legs 24 and 26 as is shown most clearly in Fig. 1.

Fig. 4 shows a modified form of the improved weatherstrip of my invention. This form of the invention contemplates the use of the same type of movable cap member 36 previously described in connection with Figs. 1, 2 and 3, but contemplates a slightly different shape of stationary body portion 22, the cross section of which is shown most clearly in Fig. 4, and forms a somewhat more compact device than that previously described. The legs 68, 70 and 72, as well as the rear of the stationary body portion 22 contact the sill or threshold 16. The rear of the stationary body portion 22 terminates in an upstanding, inwardly curved tongue portion 74 adapted to engage the groove 42 of the longitudinal rib 38 of the movable cap member 36 so that the same type of hinged pivot around which the movable cap member 36 may move is formed as that previously described in connection with Fig. 1.

A suitable hook member 58 is secured to the door 20 by any suitable means such as, for example, the screw members 60 as is shown most clearly in Fig. 4. The action of this weatherstrip is quite similar to that already described in connection with Fig. 1, the hook member 58 scissor-

ing under the movable cap member 36 when the door is closed, thus lifting the movable cap member 36 up against the bottom of the door 20 to form an effective sealing means against the entrance of wind, dust, debris, and vermin. If desired, a suitable wiper strip 62 secured to the door 20 by any suitable means such as, for example, the screws 64 may be used to provide additional protection against the entrance of wind and dust as is shown most clearly in Fig. 4. When the door 20 is opened the hook member 58 moves out from under the movable cap member 36 so that the movable cap member lies flush against the stationary body portion 22.

Figs. 5 and 6 illustrate another type of latching member from that previously described which is designed to normally hold the movable cap member 36 in place against the stationary body portion 22 and yet which permits the removal of the movable cap member 36 for cleaning and like purposes. This modified form of latching means has been illustrated in connection with Fig. 4 although it will be obvious that it could be used with equally good results with the type of weatherstrip illustrated and described in connection with Fig. 1, and also that the cam latching means shown and described in connection with Figs. 1, 2 and 3 could equally well be used in conjunction with the weatherstrip shown in Fig. 4.

This latching device contemplates the provision of a hole 76 in the top of the movable cap member 36, as well as a slot 78 cut in the outer wall of stationary body portion 22. A suitable securing member such as a rivet 80 passes through the hole 76 in the movable cap member 36 and fastens rigidly thereto. A rectangular strut 82 forms the latching member. The latching member 82 has cut therein a rectangular slot 84 through which the rivet 80 passes. The latching member 82 also has a suitable tab portion 86 which provides handle means for moving the said latching member from latched to unlatched position. Also, the lower or headed end of rivet 80 has spring 99 snapped on it, which causes a downward tension on rivet 80 and cap member 36. The tab portion 86 lies slightly above the plane of a second tab portion which has been designated by the reference numeral 88, the said second tab portion 88 forming the latching means for the device. The spring member 99, shaped as shown, passes around the rivet 80 as described, and serves to hold the assembly together as well as providing means for holding the movable cap member 36 flat against the stationary body portion 22, when the door is open. In operation, the side 90 of the latching member 82 engages the longitudinal groove 40 in the cap member 36. The tab portion 88 normally engages the groove 54 of the stationary body member 22 (see Fig. 4) so that the movable cap member 36 with the aid of spring 99 is held down against the stationary body member 22 so that the movable cap member will lie flat against the stationary body member when the door 20 is open. When it is desired to remove the movable cap member 36 from the stationary body member 22 for cleaning and like purposes, it is only necessary to slide the tab 86 to the opposite end of the slot 78 which has been cut in the outer wall of the stationary body portion 22, to a position shown most clearly by the solid lines in Fig. 5. This movement causes the latching member 82 to move in the same direction and disengages the tab portion 88 from the groove 54 in the stationary body portion 22 so that the movable cap member 36 may be removed from

the stationary body portion 22 by pulling the said movable cap member 36 forward so that the tongue portion 14 of the stationary body portion 22 no longer engages the groove 42 of the longitudinal rib 38 of the movable cap member 36 and the movable cap member may be entirely removed from the device for cleaning and other purposes. When it is desired to replace the movable cap member 36 on the device it is only necessary to engage the tongue portion 14 of the stationary body portion 22 in the groove 42 of the longitudinal rib 38 of the movable cap member 36, press the movable cap member 36 down onto the stationary body portion 22 and then move the tab 86 of the latching member 82 to the right, where it assumes the position shown by means of the dotted lines in Fig. 5, where the tab portion 88 again engages the groove 54 in the stationary body portion 22 and the movable cap member 36 is thereby held in place.

One corner of the edge of member 58 (Fig. 1 or Fig. 4) is bent down, so that as the door is closed, this corner will engage in a notch as shown at 101 in Fig. 6b which is formed under the edge of member 36 to lift this member upwardly toward the bottom of the door as it is opened and cause an air-tight cramping action of the member 36 with the stationary body portion.

Fig. 7 shows yet another modification of the improved device of my invention. This modification is especially useful in applications on casement type windows, and contemplates the provision of a stationary body member 22 which may be secured to the window sill 92 by any suitable means, such as, for example, the screw member 18. The stationary body member 22 may have the shape shown in cross-section in Fig. 7 and includes a tongue portion 94 and a longitudinal groove 96. A movable cap member 36 of the type previously described may be used in conjunction with the device, the movable cap member 36 having a longitudinally extending rib 38 having two horizontal grooves 40 and 42 cut therein, as previously described. The groove 40 of the movable cap member 36 engages the tongue portion 94 of the stationary body portion 22 to form a hinge pivot as previously described. The casement window which has been generally designated by the reference numeral 98, carries a hook member 58 which may be fixedly secured to the window by any suitable means, such as, for example, the screws 60. The hook member 58 is adapted to slip under the movable cap member 36 by a scissoring action as the window 98 is closed, as previously described, thus lifting up the movable cap member 36 as is shown most clearly in Fig. 7 and providing an effective weather seal to prevent the entrance of wind, dust, debris and vermin between the bottom of the window 98 and the sill 92. When the window 98 is opened the hook member 58 moves out from under the movable cap member 36 and the cap member lies flat against the stationary body member 22. If desired, a suitable wiper strip 62 may be carried by the window 98 to which it is fixedly secured by any suitable means, such as, for example, the screw 64. The wiper strip 62 provides additional weatherstrip protection between the bottom of the window 98 and the sill 92.

Suitable latching means such as that described previously in connection with Figs. 2 and 3 or the type described in connection with Figs. 6 and 7 may be used in conjunction with the device of the type previously described in connection with Figs. 5 and 6 being shown in Fig. 7. The latching

means provides a method for easily and quickly removing the movable cap member 36 from the device for cleaning and other purposes as has been already fully described.

It will be understood that the forms of the invention herein shown and described are to be taken as preferred and practical embodiments of the same, and that various changes may be made in shape, size and arrangement of parts without departing from the spirit of the invention or the scope of the appended claims. By way of example, the various stationary body portions 22 may have weep holes (not shown) for drainage purposes, also putty or other sealing substances may be used in conjunction with the stationary body portions 22 to provide effective sealing means along the sills and thresholds.

Having thus described the invention, what I claim and desire to secure by Letters Patent is:

1. A device of the character described including a stationary body portion having leg portions which contact the sill of a door and also having slanting flange members which also contact the sill of a door, said stationary body portion also having a web member having slanting and horizontal portions running between said legs on said stationary body portion, a movable cap member comprising a generally rectangular strip having at one side thereof a downwardly extending longitudinal rib which normally engages a flange on said stationary body member thus providing a hinge pivot around which the movable cap member may revolve, means carried by the door whereby said movable cap member is raised and interlocked with said means when said door is in closed position, said movable cap member being flush with said stationary body portion when said door is open, and latching means whereby said movable cap member is normally held on said stationary body member and providing means whereby said movable cap member may be removed from said stationary body portion for cleaning and the like, said latching means being carried by said movable cap member and engaging one side of said stationary body portion when said movable cap portion is connected to said stationary body portion.

2. A device of the character described including a stationary body portion, a movable cap member one side of said movable cap member engaging one side of said stationary body portion forming a hinge pivot around which said movable cap portion may revolve, a hook carried by a door, said hook providing means whereby said movable cap portion may be urged upwardly toward the bottom of said door when said door is closed, said movable cap portion being flush with said stationary body portion when said door is open, and latching means provided in said movable cap member whereby said movable cap member is normally held on said stationary body portion but providing means whereby said movable cap member may be removed from said stationary body portion for cleaning and like purposes, said latching means having a sliding latching member carrying a tab portion thereon, said tab portion engaging one side of said stationary body portion when said movable cap member is held in place on said stationary body portion and said tab portion capable of being moved out of engagement with the side of said stationary body portion as the sliding latch member is moved, so that said movable cap member may be removed from said stationary body portion for purposes of cleaning and the like.

3. A device of the character described including a stationary body member secured to the threshold of a door, a movable cap member one side of which is adapted to engage one side of said stationary body member to form a hinge pivot around which said movable cap member may revolve, a hook carried by said door, said hook raising said movable cap member upwardly toward the bottom of said door when said door is in closed position, said movable cap member being flush with said stationary body portion when said door is opened, latching means carried by said movable cap member, said latching means comprising a latch member which normally engages one side of said stationary body portion thus holding said movable cap member in place on said stationary body member, said latch member being capable of being slid out of engagement with said stationary body portion so that said movable cap portion may be removed from said stationary body member for cleaning and like purposes.

4. A device of the character described including a stationary body member secured to the threshold of a door, a movable cap member having one side adapted to engage one side of said stationary body portion to form a hinge pivot around which said movable cap member may revolve, a hook carried by said door, said hook raising said movable cap member upwardly toward the bottom of said door when said door is in closed position, said movable cap member being flush with said stationary body portion when the said door is opened, latching means carried by said movable cap member, said latching means including a yielding latch member which normally engages one side of said stationary body portion to hold said movable cap member in place on said stationary body portion, said yielding latch member also serving to hold said movable cap member flush against said stationary body portion when the said door is opened, said yielding latch member also being capable of being slid out of engagement with said stationary body portion so that said movable cap portion may be removed from the said stationary body portion for purposes of cleaning and the like.

5. A device of the character described including a stationary body portion having leg portions which contact the sill of a door and also having slanting flange members which also contact the sill of a door, said stationary body portion also having a flange at its upper side and a web member having slanting and horizontal portions running between said legs on said stationary body portion, a movable cap member comprising a generally rectangular strip which has at one side thereof a downwardly extending longitudinal rib which normally engages the flange on the upper side of said stationary body portion thus providing a hinge pivot around which the movable cap member may revolve, hook means carried by the door whereby said movable cap member is raised against the bottom of said door when said door is in closed position, said movable cap member being flush with said stationary body portion when said door is open, and latching means carried by said cap member said latching means including a yielding latch member which normally engages one side of the said stationary body portion to hold said movable cap member in place on said stationary body portion, said yielding latch member also serving to hold said movable cap member flush against said stationary body portion when the said door is opened, said yielding

latch member also being capable of being slid out of engagement with said stationary body portion so that said movable cap portion may be removed from the said stationary body portion for purposes of cleaning and the like.

6. A device of the character described comprising a stationary body portion for mounting on a door sill and having a tongue at one side thereof, a movable cap member comprising a generally rectangular strip having at one side thereof a downwardly extending longitudinal rib with a groove therein to pivotally receive the tongue on said stationary body portion, thereby providing a tongue and groove joint around which the movable cap member may revolve, means carried by a door whereby said movable cap member is raised and interlocked with said means when the door is in closed position, said movable cap member being flush with said stationary body portion when said door is open, and latching means whereby said movable cap member is normally held on said stationary body member and providing means whereby said movable cap member may be removed from said stationary body portion for cleaning and the like, said latching means being entirely carried by said movable cap member and engaging one side of said stationary body portion when said movable cap member is connected to said stationary body portion.

7. In a weatherstrip construction for doors, a stationary body portion adapted for mounting on a door sill, a movable cap member pivotally and releasably engaged with the stationary body portion, a door having means thereon for pivotally moving the cap member on its connection with the stationary body portion into airtight sealing position when the door is in closed position over the weatherstrip construction, the connection between the stationary body portion and the movable cap member including a tongue and groove joint that effects an airtight seal when the cap member is raised by the closing of the door, the releasable connection between the movable cap member and the stationary body portion including latching means solely carried by the movable cap member, said latching means comprising a disc cam with the effective edge of the cam normally engaged with the stationary body portion at the side thereof opposite the pivotal connection of the cap member

with the stationary body portion and means operable at the upper side of the movable cap member for releasing the connection of the cam with the stationary body portion for the separation of the movable cap member from the stationary body portion.

8. A weatherstrip construction as in claim 7, wherein the cam is biased into engaging position with the stationary body portion.

9. A weatherstrip construction as in claim 7, wherein the cam disc is rotatably mounted, and a coil spring for normally influencing the cam disc into engagement with the stationary body portion.

10. In a weatherstrip construction for doors, a stationary body portion adapted for mounting on a door sill, a movable cap member pivotally and releasably engaged with the stationary body portion, a door having means thereon for pivotally moving the cap member on its connection with the stationary body portion into air-tight sealing position when the door is in closed position over the weatherstrip construction, the connection between the stationary body portion and the movable cap member including a tongue and groove joint that effects an air-tight seal when the cap member is raised by the closing of the door, the releasable connection between the movable cap member and the stationary body portion including latching means solely carried by the movable cap member, said latching means comprising a sliding plate having a yielding latch tab normally engaged with one side of the stationary body portion to hold the movable cap member on said stationary body portion, the sliding plate being adapted to be slid out of engagement with said stationary body portion whereby the movable cap member may be disengaged from said stationary body portion.

WALTER H. HARDGRAVE.
